UNITED STATES PATENT OFFICE.

LLOYD W. BUCHENAU, OF STOCKTON, CALIFORNIA.

DESIGN FOR A GUM AND MINT CASE.

53,101.

Specification for Design.

Patented Mar. 18, 1919.

Application filed October 24, 1918. Serial No. 259,588. Term of patent 14 years.

To all whom it may concern:

Be it known that I, LLOYD W. BUCHENAU, a citizen of the United States, residing at Stockton, in the county of San Joaquin and State of California, have invented a new, original, and ornamental Design for a Gum and Mint Case, of which the following is a specification, reference being had to the accompanying drawing, forming part thereof.

The figure is a perspective view of a gum and mint case, showing my new design.

I claim:

The ornamental design for a gum and mint case, as shown.

LLOYD W. BUCHENAU.

Witnesses:

FRANK H. CARTER,
BERNARD PRIVAT.
